UNITED STATES PATENT OFFICE.

HARRY S. MOORADIAN, OF DAYTON, OHIO, ASSIGNOR TO THE DAYTON RUBBER MANUFACTURING COMPANY, OF DAYTON, OHIO, A CORPORATION OF OHIO.

DESIGN FOR A TREAD FOR TIRES.

Application filed October 26, 1925. Serial No. 15,252. Term of patent 14 years.

To all whom it may concern:

Be it known that I, HARRY S. MOORADIAN, a citizen of the United States, residing at Dayton, in the county of Montgomery and State of Ohio, have invented a new, original, and ornamental Design for a Tread for Tires, of which the following is a specification, reference being had to the accompanying drawings, forming a part thereof.

In the drawings:

Figure 1 is a plan view of the tread; Figure 2 is a section on the line 2—2 of Fig. 1.

I claim:

The ornamental design for a tread for tires, as shown.

HARRY S. MOORADIAN.
